(57) **CLAIM**

The ornamental design for a wearable medical monitor, as shown and described.

DESCRIPTION

FIG. 1 is top perspective view of a wearable medical monitor showing my new design;

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof;

FIG. 8 is a bottom perspective view thereof;

FIG. 9 is a top perspective view of another embodiment of a wearable monitor showing my new design;

FIG. 10 is a front view thereof;

FIG. 11 is a rear view thereof;

FIG. 12 is a side view thereof;

FIG. 13 is an opposite side view thereof;

FIG. 14 is a top view thereof;

FIG. 15 is a bottom view thereof, and,

FIG. 16 is a bottom perspective view thereof.

The broken lines shown in FIGS. 9 and 14 represent the bounds of the claim and form no part of the claimed design.
